UNITED STATES PATENT OFFICE.

WALTER HONORATO BARKER, OF LEYTONSTONE, ENGLAND.

ENGINE OR MOTOR.

SPECIFICATION forming part of Letters Patent No. 696,663, dated April 1, 1902.

Application filed August 3, 1901. Serial No. 70,701. (No model.)

To all whom it may concern:

Be it known that I, WALTER HONORATO BARKER, of the firm of Barker & Langcake, a subject of the King of Great Britain, residing 5 at Outgang Engineering Works, Leytonstone, county of Essex, England, have invented new and useful Improvements in Engines or Motors, of which the following is a specification.

My invention relates to engines or motors for 10 use upon motor-cars and for other purposes, and it comprises the improvements herein-after described.

My improved engine, which is specially adapted to be operated by the explosion of 15 combustible vapors, but which can also be operated by steam or other expansive fluid, comprises a number, preferably one or two pairs, of cylinders secured to a frame adapted to rotate upon a fixed shaft. This shaft carries a 20 cam or eccentric, and the cylinder-pistons, which are preferably trunk - pistons, are adapted to act upon the said cam through the medium of rollers in such a manner that their thrust against the cam will cause the cylinders to rotate around the shaft. Any suitable means may be employed for supplying 25 the cylinders with the combustible mixture or with steam or other expansive fluid. In practice I find it advantageous to arrange a 30 central plug provided with a series of ports, over which passages in the cylinders pass during the rotation of the latter. In order to insure that the pistons shall work in unison, and thereby avoid an uneven distribution of 35 weight, the pistons of each pair are connected by toggle-bars, the pins which carry the piston-rollers also serving for connecting the toggle-bars to the pistons. When two pairs of cylinders are employed, their pistons will all 40 be connected to the same toggle-bars. These toggle-bars may be made adjustable as to length to compensate for wear or the like.

When my motor is operated by the explosion of combustible mixtures, I prefer to employ 45 two pairs of cylinders and to arrange that each cylinder shall operate on the Otto cycle, so that I obtain four impulses for each revolution of the cylinders, each cylinder during one quarter of the revolution drawing in 50 the explosive charge, during the second quarter compressing the charge, during the third quarter operating under the explosion, and

during the fourth quarter exhausting the products of combustion. If desired, however, the cylinders can operate in pairs—that is to 55 say, the charges in opposite cylinders are fired simultaneously.

When the engine is used as an explosive-engine, I arrange that the several cylinders shall act as the vanes of a centrifugal fan rotating 60 in a casing, so that as the cylinders rotate a strong current of air will be induced through the casing to keep the cylinders cool. This air is also advantageously directed onto the valve-box in order to keep it cool. 65

If the engine is operated by steam, compressed air, or the like, the cylinders may be completely inclosed in a casing and the exhaust led through the said casing.

In the accompanying drawings, Figure 1 is 70 a sectional side elevation of an explosion-motor having four cylinders working with the Otto cycle and arranged for the explosive charges to be ignited in the four cylinders in succession. Fig. 2 is a section on the line 2 2, 75 Fig. 1. Fig. 3 is a side elevation of the motor. Fig. 4 is a section on the line 4 4, Fig. 2. Fig. 5 is a section on the line 5 5, Fig. 2; and Figs. 6 and 7 are two views at right angles to one another, showing an adjustable toggle-link. Fig. 8 is a section of an explosion-motor having two cylinders. Fig. 9 is a sectional side elevation of a four-cylinder explosion-motor arranged for the charges to be fired simultaneously in opposite cylinders. Fig. 85 10 is a side elevation of a four-cylinder steam-motor. Fig. 11 is a section of the distributing-valve of the motor shown in Fig. 10. Fig. 12 is a sectional side elevation of an explosion-engine, showing an arrangement for cooling by air; and Fig. 13 is a section on the line 13 13, Fig. 12. Figs. 14 and 15 are sectional views at right angles illustrating a modified arrangement of distributing and exhaust 90 valve for the gas where the cylinders are fixed 95 and the shaft rotates.

a a a a are the four cylinders, which are arranged in pairs opposite one another and are mounted in holes or sockets in the box-frame *b*, being secured in position by the bolts *b' b'*, 100 (see Fig. 4,) the said frame *b* being at one side keyed upon a sleeve or bush *b²*, rotatably mounted upon the shaft *c*, and at the other side provided with a bush *b⁰*, also rotatably

mounted upon an enlargement of the shaft c , as hereinafter described. One end of the shaft c is reduced, as shown at c' , and mounted in a bearing c^2 , which is bolted to a bar c^3 , forming a portion of the supporting-frame or bed-plate of the motor, the projecting end of the shaft c being screw-threaded to receive a nut c^4 to enable the shaft to be clamped to the bearing c^2 . Immediately in front of the reduced end c' of the shaft c a portion of the said shaft is screw-threaded, as shown at c^5 , and upon this screw-threaded portion there are mounted two half-nuts $c^6 c^6$, which are bolted in position thereon, as clearly shown in Figs. 2 and 5, and which are provided with grooves $c^7 c^7$, with which engages a collar b^3 upon the end of the bush or sleeve b^2 . By this arrangement the shaft c and bushes $b^3 b^0$ can be adjusted relatively with one another to compensate for wear. The other end of the shaft c is formed with a conical enlargement or plug c^8 , upon which the other bush b^0 of the frame rotates. This enlargement c^8 is bolted upon a bar c^9 , forming, together with the bar c^3 , the support or the bed-plate of the motor.

d is the cam which is keyed upon the fixed shaft c , the said cam being of a flattened elliptical shape.

$e e$ are the pistons, which are shown in the form of trunk-pistons, the said pistons being connected together by the toggle-links $e' e'$, the pivots e^2 , connecting the toggle-links, having mounted upon them rollers $e^3 e^3$, which bear against the cam-surface d . With this arrangement when the charges are exploded in the cylinders the pistons are driven forward in the cylinders. Their thrust being communicated to the cam-surface through the medium of the rollers $e^3 e^3$, they are constrained to follow the periphery of the said cam, carrying with them the cylinders $a a$ and the frame b , which rotates upon the fixed shaft c . The dimensions of the flattened elliptical cam are such that when a cylinder moves from one end to the other thereof its piston completes a full out and return stroke, so that for one revolution of the cylinder around the cam its piston completes two out and return strokes, thereby enabling the motor to run on the Otto cycle while still having four impulses per revolution.

f is an ignition-plug for igniting the explosive charges in the cylinder, the said plug being inserted in a hole f' in the enlargement c^8 . (See Fig. 2.) It is to be understood, however, that any other suitable form of ignition tube or gear can be employed. The hole or port f' , containing the plug f , communicates successively with holes f^2 in the bush b^0 and holes $f^4 f^4$ in the frame b , the latter being connected with ports or passages f^3 in connection with the ends of the cylinders $a a$.

g is an inlet-port and g' is the exhaust-port, both in the plug c^8 , the said two ports communicating successively with the holes $f^2 f^2$ and $f^4 f^4$ in the bush b^0 and frame b , respec-

tively, similarly to the ignition-port f' , the arrangement of the inlet, ignition, and exhaust ports being clearly shown in Figs. 3 and 4. 70

When the motor is running in the manner hereinbefore described, the passages f^3 in connection with each cylinder are successively brought opposite the inlet-port g , so that a charge is drawn into the cylinder and compressed, brought opposite the ignition-port f' , and finally opposite the exhaust-port g' , where the products of combustion are driven out by the second return stroke of the pistons. It will thus be seen, as above described, that 80 the motor receives four impulses per revolution, each piston drawing in its charge, compressing it, being driven out by the expansion of the charge on explosion, and finally driving out the products of combustion, being then ready to draw in a fresh charge for the next revolution of the engine.

h is the casing of the motor, the said casing being fixed in position and being provided at its lower part with an inlet h' for water and 90 at its upper part with a pocket h^0 , having an outlet h^2 for the water, the said water which serves to cool the motor being circulated through the casing in contact with the cylinders through the medium of vanes h^3 , which 95 are secured to the cylinders and which when the cylinders rotate in the casing serve as a centrifugal pump and draw the water through the inlet h' and drive it into the pocket h^0 and out through the outlet h^2 , the motor rotating in the direction of the arrow, Fig. 1.

Figs. 6 and 7 show toggle-links which are adapted to be adjusted in length, this being effected by making the links $e' e'$ in halves, which are connected together by a rod i , provided at its two ends with right and left hand screw-threads, respectively, and having a hexagon portion i' , by means of which it can be turned so that it can shorten or lengthen the rods. $i^2 i^2$ are nuts for locking the rods i in position.

In Fig. 8 I have shown a motor provided with two cylinders arranged diametrically opposite to one another. In other respects the principle of the construction of this motor is identical with that previously described. In lieu of the two other cylinders chambers $j j$ are provided, within which the rollers $e^3 e^3$ can move.

Fig. 9 illustrates a four-cylinder explosion-120 engine in which the charges instead of being fired in the cylinders in succession are fired in two opposite cylinders simultaneously. To this end the passages $f^3 f^3$ of the opposite pairs of cylinders open into a common passage k in the frame b and the bush b^0 , the inlet, ignition, and exhaust ports being preferably arranged as shown in the drawings.

In Figs. 10 and 11 I have shown my improvements applied to a steam-engine. The 130 construction of this motor is similar to that hereinbefore described; but in this case two inlet-ports $g g$ are shown arranged diametrically opposite to one another and which sup-

ply the pair of oppositely-placed cylinders simultaneously. There are also two exhaust-ports $g' g'$, which are also arranged diametrically opposite to one another, so that each 5 pair of cylinders exhaust simultaneously, the said exhaust-ports communicating by pipes $g^2 g^2$ with the inside of the casing h of the motor, the exhaust-steam being discharged from the said casing h through the discharge-opening h^2 .

In the arrangement illustrated in Figs. 12 and 13 the motor-cylinders are provided with transverse webs $l l$ for cooling purposes, and a current of air is directed against these webs 15 by means of the fans $m m$, secured in connection with the rotating box-frame b . Plates $n n$ are fitted in the angles between the cylinders, so as to divide the space inside the casing into two halves. By this arrangement 20 the air drawn in by each fan is driven against the partition-plates n and thus deflected upward over the whole of the surfaces of the cylinders, the centrifugal action of which drives the air out.

25 It will be obvious that in lieu of arranging for the cylinders to rotate upon a fixed shaft by means of the cam the cam itself can be caused to rotate, in which case the cylinders are suitably fixed and the shaft c is rotatably 30 mounted in bearings, as indicated by the dotted lines at $o o$, Fig. 8. A suitable form of distributing-valve for a motor of this description is shown in Figs. 14 and 15, in which in addition to the ports $f^2 f^2$, communicating 35 with the passages $f^3 f^3$, as in Figs. 1 to 4, I provide in the frame b , in connection with the ignition-port f' , the inlet g , and the exhaust g' in the plug c^8 , annular passages p , q , and r , respectively, each having four ports 40 opening to the plug c^8 , corresponding in position with the four ports $f^2 f^2$. The shape of the port f' is shown clearly in Fig. 14, the other ports g and g' being of similar shape, but shorter in length.

45 Having now particularly described and ascertained the nature of my said invention and in what manner the same is to be performed, I declare that what I claim is—

1. In an engine, the combination with a 50 shaft, of a casing surrounding the same, said casing and shaft being the one revolvable with respect to the other, said casing being provided with plurality of cylinders, pistons in said cylinders provided each with a cam-engaging roller, a cam secured to said shaft and adapted to be engaged by said roller, and means for moving the unactuated pistons, substantially as described.

2. In an engine, the combination with a 60 shaft of a casing surrounding the same, said casing and shaft being the one revolvable with respect to the other, said casing being provided with a plurality of cylinders, pistons in said cylinders provided each with a cam-engaging roller, a cam secured to said shaft and adapted to be engaged by said rollers, and means whereby the actuation of a part

of the pistons will give the unactuated pistons the necessary movement to continue the operation of the engine, substantially as described.

3. In an engine, the combination with a shaft, of a casing surrounding the same, said casing and shaft being the one revolvable with respect to the other, a plurality of cylinders 70 secured to said casing, pistons in said cylinders, provided with cam-engaging rollers, a cam secured to said shaft and adapted to be engaged by said rollers and connections between said pistons, substantially as described.

4. In an engine, the combination with a shaft, of a casing surrounding the same, said casing and shaft being the one revolvable with respect to the other, a plurality of cylinders 75 secured to said casing, pistons in said cylinders, provided with cam-engaging rollers, a cam secured to said shaft and adapted to be engaged by said rollers and adjustable connections between said pistons, substantially as described.

5. In an engine or motor the combination of one or more pairs of cylinders, the pistons of which are connected by toggle-links, of a frame to which the cylinders are secured, of 95 a shaft upon which the frame is mounted and of a cam keyed upon the shaft and against which rollers carried by the toggle-links bear, substantially as described.

6. In an engine or motor the combination of one or more pairs of cylinders, the pistons of which are connected by toggle-links carrying rollers, of a frame to which the cylinders are secured, of a fixed shaft upon which the frame is rotatably mounted and of a cam 100 keyed upon the shaft and against which the aforesaid rollers bear, substantially as hereinbefore described.

7. In an engine or motor the combination of one or more pairs of cylinders, the pistons of which are connected by toggle-links, of a 105 frame to which the cylinders are secured, of a shaft upon which the frame is mounted, of a cam keyed upon the shaft and against which rollers carried by the toggle-links bear, and of a distributing-valve in connection with the 110 shaft for the steam or explosive charge, substantially as described.

8. In an engine or motor the combination of one or more pairs of cylinders, the pistons of which are connected by toggle-links, of a 120 frame to which the cylinders are secured, of a shaft upon which the frame is mounted, of a cam keyed upon the shaft and against which rollers carried by the toggle-links bear, of a casing inclosing the cylinders and having an 125 inlet and outlet for cooling fluid and of vanes in connection with the rotating shaft or cylinders for circulating the cooling fluid, substantially as described.

9. In an engine or motor the combination 130 of one or more pairs of cylinders, the pistons of which are connected by toggle-links carrying rollers, of a frame to which the cylinders are secured, of a shaft upon which the frame

is rotatably mounted and of a cam against which the aforesaid rollers bear and of means for adjusting the length of the toggle-links, substantially as described.

- 5 10. In an engine, the combination with a casing provided with a pair of oppositely-disposed cylinders, pistons in said cylinders each provided with a cam-engaging roller, a cam adapted to be engaged by said rollers, connections between said pistons, and cam-engaging rollers carried by said connections, substantially as described.
- 10 11. In an engine, the combination with a

15 shaft and a casing surrounding said shaft, a pair of cylinders secured to said casing, pistons in said cylinders each provided with a cam-engaging roller, a cam secured to said shaft and adapted to be engaged by said rollers, toggle-levers connecting said pistons and cam-engaging rollers carried by said toggle-levers, substantially as described.
